UNITED STATES PATENT OFFICE.

WILFRED LEWIS, OF HAVERFORD, PENNSYLVANIA.

METHOD OF CASTING CHAINS.

1,307,136.

Specification of Letters Patent. Patented June 17, 1919.

Application filed January 12, 1918. Serial No. 211,657.

To all whom it may concern:

Be it known that I, WILFRED LEWIS, a citizen of the United States, and a resident of Haverford, in the county of Montgomery and State of Pennsylvania, have invented a certain new and useful Method of Casting Chains, of which the following is a specification.

The principal object of the present invention is to provide a simple, comparatively inexpensive and expeditious method of casting chains which may be of steel and of the stud variety.

Generally stated the method consists in making core-sand molds with fusible half link patterns or forms and in the case of stud chains with half stud patterns or forms, in the case of stud chains drawing the stud patterns or forms and baking the sand and melting out the fusible patterns or forms to make destructible mold sections each containing two half link matrices, arranging the mold sections face to face to provide link matrices in adjoining sections, pouring these separate matrices to cast the chain, and destroying the mold sections to remove the chain.

The accompanying drawing are illustrative of the invention and of certain apparatus that can be employed in the practice of the same.

In the drawings, Figures 1 and 2 are sections taken at right angles to each other and illustrating the arrangement of the patterns in the flask.

Fig. 3, is a top view of the flask.

Fig. 4, is a section on the line 4—4 of Fig. 3.

Figs. 5 and 6, illustrate the core-sand mold before and after baking.

Fig. 7, is a side view, partly in section, illustrating the molds arranged for pouring.

Fig. 8, is a section on the line 8—8 of Fig. 7, and

45 Figs. 9 and 10, are top or plan views diagrammatically illustrating the manufacture of a chain by making it in sections and then joining the sections together.

50 The half link forms 1 and 2, are made of fusible metal, such as lead or an alloy thereof, and can be readily cast, for example, in

iron molds. They are arranged in the flask 3 in such a way that the form 1 is supported as by means of feet 4 from pattern plate 5 at the bottom of the mold, and the form 2 55 is suspended through, but not in contact with, the form 1. The form 2 is shown as suspended by heads 6, arranged between a pair of bars 7 and 8, supported on the top of the flask 3. In making a stud chain, one 60 of the half stud patterns 9 is secured to the pattern plate 5, and the other half stud pattern 10 is secured by a head 11 arranged between the bars 7 and 8. 12, is a sand frame that may be applied to the top of the 65 flask and through suitable openings in which extend the ends of the cross-bars 7 and 8.

The pattern plate 5 is provided with a gate 13 and use may be made of non-fusible dowel pins 14, supported in suitable sockets 70 in the pattern plate 5, and of patterns 15, supported from the cross-bars and adapted to make openings for the reception of the dowel pins. The parts being arranged substantially as shown in Figs. 1 and 2, the flask 75 is rammed with core-sand, or its equivalent, the flask frame is removed permitting the bars 7 and 8 to be separated and removed, the sand is struck off, the patterns 15, 13 and 10 are drawn, as is also the pattern 9, 80 leaving what may be called a core-sand mold containing within it the fusible patterns or forms 1 and 2 and otherwise having matrices 16 formed by the withdrawal of the patterns 15 and matrices 17 and 18, formed by the 85 withdrawal of the patterns 9 and 10. The mold also has a runner 19 (Fig. 3) and it may be remarked that the runners 19 extend in opposite directions in different molds or, in other words, some molds are "rights" and some are "lefts", as is evident from Fig. 8. 90

The core-sand mold in the general condition illustrated in Fig. 5, is then baked and for this purpose it may remain in the hinged flask 3 (Fig. 3). As a result of the baking 95 the fusible forms or patterns 1 and 2 run out and the mold becomes sufficiently hard and strong for casting, yet readily destructible. Each mold section then is illustrated in Fig. 6, and contains two non-communicating matrices *a* and *b*, each of the form of a half link and it may be provided with 100

dowel pins 14 and corresponding cavities 16 therefor. A series of these baked core-sand mold sections are then arranged face to face, as shown in Fig. 7, for example in 5 a suitable frame 21 to provide one complete link matrix in each pair of adjacent molds, there being one runner for each complete link matrix. The dowel pins, when present, serve to insure proper alinement, as does 10 also the polygonal form of the molds and of the frame 21.

Each mold or mold section is an integral structure and has opening through two of its faces, the open ends of looped non-communicating part-link matrices, and in the 15 assemblage of these separate integral mold sections the open ends of these part-link matrices are alined to make link matrices. Runner boxes 22 may be applied for pouring metal into two adjacent molds, within 20 which there is formed one complete link, and a repetition of this operation produces the chain of links.

The mold sections are destroyed to remove 25 them from the chain and this can be accomplished by the simple operation of shaking the chain, or in any other convenient way.

The fusible metal which runs out of the 30 core-sand molds when they are baked and which constituted the forms 1 and 2 can be returned to the melting pot for use in molding additional forms 1 and 2, as has been above referred to.

35 From the foregoing description it is evident that the length of the chain depends upon the number of mold sections employed and is unlimited, except by practical consideration of space and the like. Ordinarily the half link matrices at the extreme ends of the series of mold sections would not be poured. However, two series of chains when poured can be joined by putting their end molds face to face and then pouring the 40 connecting link. Referring to Fig. 10, a number of rows A and B of mold sections assembled as above described, of lengths depending upon the size and convenience of the foundry, are laid down. To make a 45 chain, for example 1000' long, it would be hardly possible to secure a floor of that length, and ten rows of 100', twenty rows of 50', or any convenient number of rows aggregating the total length desired can be used 50 on the available floor space. The rows may be parallel with room between them for setting and pouring, then after pouring these molds and casting separate lengths of chain and allowing them time to cool enough for 55 handling a few links are freed from the chain near the end of each row, as shown at D by dotted lines, keeping the end molds undisturbed so as to be shifted and brought into contact as indicated in Fig. 9. Then the

final link can be poured, uniting two rows 65 of chain, and finally the floor will resemble a great snake as shown in Fig. 10. Care must be exercised to position the end molds in adjacent rows to be united in such manner that they will come together properly. In 70 this way it is evident that a chain of almost any length can be made within a foundry of reasonable size. By the use of baked core-sand molds, instead of green sand, better castings are obtained especially in steel. 75

Any fins that may adhere to the chain and which correspond to the runners, or are produced thereby, may be broken off and ground if necessary.

What I claim is:

1. The process of making chains which consists in making core-sand molds with fusible spaced half link patterns or forms, baking the core-sand molds and melting out the fusible patterns or forms to make destructible 85 mold sections each containing two non-communicating half link matrices, arranging the mold sections face to face with the partings cross-wise of the length of the chain to provide link matrices partly in adjoining 90 sections, pouring these separate link matrices to cast the chain, and destroying the mold sections to remove the chain.

2. The process of making chains which consists in making core-sand molds with fusible half link patterns or forms and with half stud patterns or forms, drawing the half stud patterns or forms and baking the core-sand molds to run out the fusible patterns or forms to make destructible mold 100 sections each containing two non-communicating half link matrices and half stud matrices, arranging the mold sections face to face to provide link matrices partly in adjoining sections, pouring these separate link 105 matrices to cast the chain, and destroying the sections to remove the chain.

3. The process of making chains which consists in making molds each containing two non-communicating half link matrices 110 and arranging the molds face to face to provide link matrices partly in adjoining molds, pouring these separate link matrices to cast the chain, and destroying the molds to remove the chain.

4. The process of making chains which consists in making molds each containing two duplicate non-communicating half link matrices opening through the opposite faces of the molds, arranging the molds face to 120 face with the matrix openings in alinement to provide link matrices partly in adjoining molds, pouring the separate link matrices to cast the chain, and destroying the mold sections to remove the chain.

5. The process of making chains which consists in making integral destructible molds having open half-link matrices, ar-

ranging such molds in series with the open half-link matrices in alinement to provide complete link matrices, pouring the matrices, and destroying the molds to remove the 5 chain.

6. The process of making chains which consists in making baked integral molds hav-

ing spaced and locked half-link matrices extending through two of their faces, arranging a series of such molds face to face to 10 provide complete link matrices, pouring the complete matrices, and destroying the molds to remove the chain.

WILFRED LEWIS.
